JULIUS BING, OF EISENACH, GERMANY, ASSIGNOR TO THE FIRM MAGNET-WERK G.M.B.H. EISENACH SPEZIALFABRIK FÜR ELEKTROMAGNET-APPARATE, OF EISENACH, GERMANY

METHOD AND APPARATUS FOR TRACING METALLIC BODIES IN FABRICS

Application filed December 11, 1928, Serial No. 325,168, and in Germany March 3, 1928.

My invention relates to an examination of flat goods, especially of textures, which consists in tracing castal metallic bodies, especially needles or broken parts thereof, which may be accidentally contained in such goods.

In the weaver's trade great difficulties arise from the occurrence of thin metallic needles in the textures since the said needles lead to the tearing of the fabric and may also, by rusting, give rise to spots or stains. Attempts have already been made to devise an automatic appliance for removing needles from the web of fabric during the manufacturing process. Such attempts have been made both with magnetic and with mechanical means, but hitherto without success. It has also already been proposed to employ the electrical contact action of a needle in passing over rollers for the giving of a signal. These attempts have also led to no success, since, if the needle is unfavourably placed in the web of fabric the latter has itself an insulating action and thus prevents the contact effect.

My invention obviates all these difficulties in the following manner. The web of fabric to be examined for needles or the like is passed between metallic fabric feeding and guiding rollers functioning also as high potential electrodes which are electrically insulated from one another, and to each fabric feeding and guiding roller an electrical voltage is supplied by means of a suitable small high voltage transformer. The fabric feeding rollers are placed so close together that the cloth can just pass between them, without an electric contact being closed through the said rollers, owing to the insulating action of the intervening fabric.

Now, if an electrically conducting foreign body, such as a needle embedded in fabric, for example, passes between the fabric feeding and guiding rollers, the air gap is shortened by the metal of the needle, and a slight spark discharge occurs between the two rollers at the point where the needle is passing. As a result of this, the current conditions of the electric circuit including the corresponding winding of the transformer alter in such a way that in the other winding of the transformer the increasing current strength can

be utilized for actuating an automatic electrical device for the purpose of immediately stopping the machine, through the medium of a relay, for example. The operator can then easily remove the needle or the like.

In the drawings an embodiment of my invention consisting in an apparatus for automatically tracing needles and other metallic bodies in textures is illustrated.

Fig. 1 is a schematic view of the entire apparatus with a wiring diagram of the electric part of the apparatus, the rollers for feeding the texture to be examined being only partly shown and the clutch for controlling the drive of the rollers being partly shown in side elevation and partly in a longitudinal section. Fig. 2 is a side elevation of a pair of rollers for feeding the texture to be examined.

1, 2 are two cooperating feed rollers the surfaces of which consist of a metal or another material conducting electricity. The length of the said rollers corresponds with the breadth of the texture 3 to be examined, whilst the gap between the cooperating superimposed rollers corresponds with the thickness of the said texture. The rollers are mounted in bearings 4, one of which is shown in Fig. 1. The rollers are mounted in such a way that the two rollers are electrically insulated from each other. For this purpose the bearings of the upper roller 1 may be mounted in the respective platform with the application of an intermediate bushing 5 of insulated material.

The lower roller 2 may be rotated from any source of energy, and according to the embodiment of the invention illustrated in the drawing the said roller is driven through the intermediary of an electromagnetically actuated friction clutch 6 which substantially consists of three parts, the magnet body 8, being fixed on the driving shaft 7 of the roller 2 and encasing the exciting coil 9, the armature disc 10 cooperating with the magnet body and being loose on the shaft 7 and the pulley 11 which is non-rotatably mounted on the armature disc and driven by a belt 12.

The exciting current is fed from the circuit 14 to the exciting coil 9 by means of slip rings 10a

13. The circuit 14 includes a source of electricity 15 and a pair of contacts 16.

On the shafts of the rollers 1 and 2 contacts 17, 18 are sliding which are connected by conductors 19, 20 with the secondary or high-voltage coil 21 of a small transformer 22. The primary or low-voltage coil 23 of the said transformer lies in an alternating current circuit 25 which also contains the coil 26 of a relay 27 and is fed from a source 24. 28 is the armature of this relay, and a spring 29 tends to move said armature away from the magnet core 30 of the relay.

On the armature 28 a contact 31 is provided which is normally in touch with two contacts 32 of a circuit 33 which includes the source of current 34 and the coil 35 of a second relay 36, the armature 37 of which is provided with a contact 38 through which short circuit 20 is produced between the two contacts 16 mentioned above.

The operating of the apparatus is as follows: According to Fig. 1 the circuit 14 including the exciting coil 9 of the clutch 6 is closed by the armature 37 of the relay 35. In consequence thereof the clutch 6 is engaged so that the pulley 11 is fixed to the shaft 7 and the roller 2 is rotated. The texture 3 to be examined is now fed through the gap between the said roller 2 and the upper roller 1 and taken along by the roller 2 whereby the surfaces of the rollers are in close contact with both sides of the texture.

If now the fabric contains a needle or the like which may project on the one or the other side of the fabric or be fully embedded in the texture, and the said needle passes the rollers 1, 2, the electrical conditions in the circuit including the rollers 1, 2 as electrodes 40 and the secondary coil 21 of the transformer are altered.

Normally the said alteration will result in an electric discharge which in accordance with the position of the foreign metallic body 45 relative to the rollers 1, 2 will take place between the foreign body and one of the rollers or between the foreign body and both of the rollers.

On the primary side of the transformer 22 the alteration generally results in a strengthening of the current in the circuit 25. In consequence thereof the armature of the relay 27 is attracted against the action of the spring 29. Thereby the circuit 33 is interrupted on the contacts 32, and the relay 36 correspondingly switched off so that the armature 37 of said relay moves downward and interrupts the circuit 14 whereby the electromagnetic clutch is switched out. The drive of the roller 2 is now interrupted and the fabric stopped so that the foreign body may easily be removed from the fabric.

The energy of the small spark discharge that occurs is kept so small, preferably by 60 the use of small transformers, that it is not

sufficient to produce any visible effect on the cloth. Experiments have shown that this apparatus is exceedingly sensitive and operates in an absolutely reliable manner. It makes the machine entirely independent of the attention of the operator since it stops the machine automatically whenever such disturbing needles or the like occur in the fabric.

For the inventive idea it is a matter of indifference whether the high voltage is produced as indicated in the accompanying drawing by an alternating current transformer or by any suitable continuous current apparatus. The essential point is that the needles or the like passing between the two rollers of the apparatus serve by diminishing the air gap to produce an alteration of the electric conditions of the controlling circuit.

Instead of the two rollers, plane surfaces may be employed, between which the web of fabric passes. This detail is immaterial so far as the invention is concerned. Alternatively, one roller might co-operate with one plane surface.

I claim:

1. An apparatus for automatically searching for metallic bodies such as needles in textile fabrics, comprising an electric circuit, electrodes in said circuit, one of said electrodes forming a driven roller adapted to convey the fabric to be examined, an electric transformer having a high voltage winding and a low voltage winding, the high voltage winding being inclosed in the said electric circuit, an electromagnetic clutch adapted to interrupt the rotation of the said roller and an electric relay in the said low voltage winding adapted to disengage the said clutch.

2. Apparatus for automatically searching for metallic needles in textile fabrics, comprising an electric circuit, two rollers electrically insulated from each other and spaced apart from each other so as to be able to receive the fabric to be controlled between them, means for rotating said rollers, an electric transformer, having a high voltage and a low voltage winding, an electric circuit inclosing said rollers and said high voltage winding, a clutch adapted to stop said rotating means, and an electric relay inserted in said low voltage winding and adapted to disengage said clutch.

3. In an apparatus for detecting metal particles in non-metallic material, an electric circuit including a high tension current source and two electrodes between which the material to be examined is passed, and means responsive to changes in the electric conditions of said condenser.

4. In an apparatus for automatically tracking metallic foreign bodies in fabrics or the like, an electric circuit including two metallic rollers normally electrically insulated from each other, means for feeding said fabric be-

tween said rollers, said feeding means being normally operative while the fabric is passing between said rollers, means responsive to discharges of said circuit due to foreign bodies in the fabric, said responsive means controlling said feeding means and wherein said rollers form the feeding means for said fabric.

5. A method of automatically tracing casual metallic bodies embedded in fabrics which consists in passing fabric in fabric feeding and guiding contact between fabric feeding and guiding high potential roller electrodes contained in a high tension electric circuit 10 and in utilizing for the controlling of the fabric movement the alterations of the electric conditions of said circuit due to the presence of an embedded metallic body in that portion of fabric between said high potential 15 roller electrodes.

6. A method of automatically tracing casual metallic bodies embedded in fabrics, which consists in passing fabrics in fabric feeding and guiding contact between fabric feeding 20 and guiding high potential electrodes contained in a high tension electric circuit, and in utilizing for the control of the said feeding electrodes, spark discharges as metallic bodies embedded in said fabrics pass between 25 said fabric feeding high potential electrodes.

7. In apparatus for tracing casual metallic bodies embedded in fabrics comprising a high tension electric-circuit, fabric-feeding and guiding high potential electrodes in said circuit, said fabric being in fabric feeding and guiding contact with each of said electrodes, said electrodes being insulated each from the other, and means for stopping the feed of said fabric when a metallic body embedded in said 30 fabric is present between said high potential electrodes.

8. In apparatus for tracing or searching out casual metallic bodies embedded in finished fabrics, means for feeding said fabrics, a high tension electric circuit, high potential electrodes in said circuit, said fabric being normally in contact with each of said electrodes; and means for stopping the feeding of said fabrics, when a metallic body is found 35 in said fabric between the said electrodes.

9. An apparatus for tracing or searching out extraneous metallic bodies, embedded in fabrics; electric circuits; fabric feeding high potential electrode roller devices operatively 40 included in said circuits; and means for stopping the mechanical operation of the said fabric feeding high potential electrode roller devices through the presence of an embedded metallic body in the fabric between said electrodes.

10. In an apparatus for feeding and examining fabrics and other strip material for the presence of extraneous metallic bodies, insulated high potential electrodes arranged 45 in constant contact with the opposite side

faces of said fabric, and means for stopping the feeding movement of said fabric when a metallic body is present in that portion of the fabric between said electrodes.

In testimony whereof, I affix my signature. 70
JULIUS BING.
